(57) **CLAIM**

We claim the ornamental design for low profile fixed display mount, as shown.

DESCRIPTION

FIG. 1 is a front perspective view of a low profile fixed display mount;

FIG. 2 is top plan view of the low profile fixed display mount depicted in FIG. 1;

FIG. 3 is a rear elevation view of the low profile fixed display mount depicted in FIG. 1;

FIG. 4 is a side elevation view of the low profile fixed display mount depicted in FIG. 1;

FIG. 5 is a front elevation view of the low profile fixed display mount depicted in FIG. 1;

FIG. 6 is an opposing side elevation view of the low profile fixed display mount depicted in FIG. 1; and,

FIG. 7 is a bottom plan view of the low profile fixed display mount depicted in FIG. 1.
